UNITED STATES PATENT OFFICE.

WILLIAM E. DWYER, OF LEADVILLE, COLORADO.

DUST-ARRESTING AND AIR-PURIFYING DEVICE.

983,882.

Specification of Letters Patent. Patented Feb. 14, 1911.

Application filed January 28, 1910. Serial No. 540,643.

To all whom it may concern:

Be it known that I, WILLIAM E. DWYER, a citizen of the United States, residing at Leadville, in the county of Lake and State 5 of Colorado, have invented certain new and useful Improvements in Dust-Arresting and Air-Purifying Devices, of which the following is a specification, reference being had to the accompanying drawings.

10 My invention relates to improvements in dust-collecting and air-purifying devices for use in connection with pneumatic rock drills and the like.

One object of the invention is to provide 15 a device of this character which will not only collect the dust produced by the drill but will also purify the air coming from the drill by the removal of very fine particles of ore and other impurities which are so injurious to life in sulfur and lead mines.

20 Another object of the invention is to provide a device of this character which may be used with the ordinary mining drills and which needs no special tool or appliance to 25 permit of its use in connection with pneumatic rock drills.

Further objects of the invention are to 30 improve the construction and operation of devices of this character and thereby render them more efficient and less expensive.

With the above and other objects in view, the invention consists of the novel construction, combination and arrangement of parts, hereinafter fully described and claimed, and 35 illustrated in the accompanying drawings in which:—

Figure 1 is a longitudinal section through one embodiment of my invention showing the use of the same; Fig. 2 is a side elevation 40 of the device; Figs. 3 and 4 are sectional views taken on the lines 3—3 and 4—4 in Fig. 1; Fig. 5 is a perspective view of the tubular member or mouth piece which enters the drill hole; Fig. 6 is a side elevation of a modified form of the invention; Fig. 7 is a longitudinal section through parts shown in Fig. 6; Figs. 8 and 9 are transverse sectional views taken on the lines 8—8 and 9—9 in Fig. 6; Fig. 10 is a perspective view of the tubular member or mouth piece shown in Fig. 6; Fig. 11 is a side elevation of another form 50 of tubular member or mouth piece; Figs. 12 and 13 are longitudinal and transverse sectional views through the same; Fig. 14 is a longitudinal section through another embodiment of the invention; Figs. 15 and 16

are detail sectional views taken respectively on lines 15—15 and 16—16 in Fig. 14; and Fig. 17 is a perspective view of the tubular member or mouth piece shown in Fig. 14. 60

Referring more particularly to Figs. 1 to 5 inclusive of the drawings the numeral 1 denotes a casing or sheath arranged to surround an ordinary bit B of a drilling machine M and adapted to have at one end an air-tight joint or connection with the drill hole H, and at its other end an air-tight connection with a drill or other portion of the machine M. The casing 1 is adapted to serve both as a dust-collecting chamber, and 70 also as a purifier or filter. The latter object may be accomplished in different ways, for example, it may be attained by making the casing of fabric which is sufficiently porous to permit of the escape of air without allowing any of the fine particles of dust, ore or other impurities to escape, as hereinafter more fully explained; or said casing may be made of other flexible material of a heavier 75 nature such as canvas or similar fabric or 80 leather, in which case it is provided with an outlet opening or portion covered with a suitable screen or screening material which will allow the escape of air and effectively prevent the escape of impurities. 85

As illustrated in Fig. 1 the casing or chamber 1 is provided at its rear with a tubular outlet portion or pocket 2 which is covered with or contains a sponge 3 which will serve as a filter or screen, but it will be 90 understood that a fine wire screen or one of other form and construction which will effect the desired result, may be employed in lieu of the sponge. By making the casing porous or of non-porous material and providing it with a filter or screening substance it will be seen that the escape of injurious particles of dust and other impurities will be effectively prevented so that the air coming from the pneumatic drill will be purified and rendered non-injurious to those 95 working in the mine. The chamber or casing 1 may be of any size, shape and construction, but as illustrated in Fig. 1 it is of rectangular shape and depends from the 100 drill, the latter passing through its upper portion. 105

The air-tight joint or connection between the chamber or casing 1 and the drill hole may be effected in various ways but I preferably provide a tubular member or mouth piece 4 of such construction that it may be 110

inserted in an ordinary drill hole. It is well understood by those versed in the art that drill holes used in mining operations are made by a set of drill bits, usually six in 5 number and graduated in size, the one first used being the largest so that the outer end of the hole is of greater diameter than the inner end or bottom. I therefore construct the tubular member or mouth piece 4 so that 10 it may be inserted in the outer end of an ordinary drill hole in order to dispense with the necessity of using extra bits or tools to enlarge the drill hole. I therefore make the tubular member or mouth piece of tapered cylindrical form and diametrically expandible so 15 that it can be inserted in holes varying in size. It is preferably formed from a single plate of resilient sheet metal bent into substantially cylindrical form and preferably 20 having its edges overlapping, as shown more clearly in Figs. 4 and 5. When thus constructed it may be contracted to permit of its insertion in the hole H and when it is released it will expand in the hole to provide 25 a tight joint or connection. The projecting outer end of the mouth piece 4 is adapted to be connected to the casing or chamber 1, such connection being preferably 30 effected by forming on the casing a tubular neck 5 to receive the mouth piece, which neck, like the casing is made of flexible fabric, and by providing means of contracting the neck 5 around the mouth piece to retain the parts in engagement at any 35 diametrical adjustment of the mouth piece. This may be accomplished by employing an annular elastic band 6 of rubber or the like and by providing on the mouth piece or member 4 stop lugs 7. These lugs are shown 40 in Fig. 5 as being integral with the mouth piece 4 and formed by making parallel slits in the end of said mouth piece and bending outwardly the tongues formed by said slits.

In Figs. 14, 15 and 17, of the drawings I 45 have shown a tubular member or mouth piece 4' which is quite similar to the one just described, it being constructed of a sheet of resilient metal bent into tubular shape and having the edge of its large outer end 50 bent or folded outwardly to provide a retaining bead or flange 7' which serves the purpose of the stop lugs 7. The neck 5' of the casing or chamber 1' is provided with a hem 5' which contains a drawing string 6' 55 adapted to retain the neck 5' on the mouth piece 4', as will be readily understood on reference to the drawings.

In the embodiment of the invention illustrated in Figs. 14 to 17 inclusive the casing 60 1' is preferably made of substantially circular shape and it is constructed of a fabric material sufficiently porous to permit of the escape of air but which will prevent the passage of dust and other impurities; and 65 owing to it being constructed of such mate-

rial it is not provided with an extra screen or filtering member, the fabric material itself forming the filtering or screening substance.

The air-tight joint or connection between 70 the casing or chamber 1 in Fig. 1 and the drill or machine may be effected by providing on the upper portion of the rear edge of the casing a flexible, diametrically adjustable, tubular neck or extension 8 through which the drill extends, and which is adapted to be wrapped close around the drill by a cord, strap or the like, 9 which has one of its ends attached at 10 to said neck, and its other end attached to a weight 11. The intermediate portion of the strap 9 is wrapped 75 once around the neck 8 so that the weight will draw the strap tight and cause it to bind the neck upon the drill or other part of the machine.

Instead of employing the strap and weight just described I may substitute a spring clip 12 shown in Fig. 6 of the drawing. This clip consists of a substantially circular spring which surrounds the neck 8' of the 90 casing 1' and which has one of its ends attached by a rivet 13 and reinforcing plate 14 to said neck.

In Figs. 14 and 17 of the drawings I have shown another form of connection between 95 the casing and the bit or drill, the same comprising a tubular neck 8' which is wrapped around the bit and which receives a spring clip 12' similar to the clip 12. The clip 12', however, is not attached to the neck 8' but 100 has an outwardly bent apertured end through which passes an attaching cord 12', the latter having one end secured to a loop or tab 12' on the casing 1', and the other end of 105 said cord being knotted to prevent the spring clip from slipping off of the cord and becoming lost.

In Figs. 6, 7 and 8, of the drawing I have 110 illustrated another form of tubular member or mouth piece which may be used on the casing for the purpose of effecting an air-tight connection with the drill hole. This tubular member is likewise constructed of a piece of resilient sheet metal bent to form 115 a longitudinally split cylindrical tube 4'. The casing 1' has at the upper portion of its front end a tubular neck or extension 5' which is adapted to receive the tubular member 4'. The neck 5' has at its front end a rearwardly turned surrounding portion 15 120 which may be formed integral with said neck or attached thereto, said part 15 being of course formed from flexible material and preferably of canvas or other fabric so as to serve as a packing to engage the wall of the 125 drill hole. To maintain this packing member or flange 15 in close engagement with the wall of the drill hole I provide on the outer end of the tube or member 4' rearwardly turned spring arm 16, which latter may be 130

formed integral with said tube or member and which are disposed beneath the packing flange 15 to actuate the same outwardly. To further expand the packing flange or member 15 I may provide around the tube or member 4^a and the neck 5^a an expanding coil of round or flat resilient wire. This coil is designated by the numeral 17 and is of conical form, its small front end having connected to it at opposite points rearwardly extending operating arms 18 which are disposed within the coil and which have outwardly bent finger pieces 19 at their rear ends. It will be seen that when the finger pieces 19 are grasped and the arms 18 are sprung together the small front end of the cone-shaped coil will be contracted to contract the member or tube 4^a and thereby enable it to be readily inserted in the drill hole, and that when said arms are released the resiliency of the coil will expand the packing flange 15 or assist the arms 16 in expanding the same.

In Figs. 11, 12 and 13, of the drawings I have shown still another form of expandable mouth piece for effecting an air-tight joint between the collecting casing or chamber and the drill hole. This mouth piece comprises a tubular member 4^b in the form of a cylindrical band or ring which is riveted or otherwise secured on the inside of a tubular neck 5^b formed on the casing or chamber 1^b. The ring or band 4^b is secured adjacent to the outer edge of the neck 5^b and said edge or end of the latter is then folded back over the ring or member 4^b. The folded part or flange 15^b of the neck 5^b is adapted to serve as a packing and it is expanded by arranging within it a split expanding ring 20 constructed of resilient metal and adapted to be contracted and expanded by a pair of tongs consisting of cross levers 21 pivotally united at their points of intersection and having their front ends secured to the expanding ring or band 20 adjacent its spaced ends, the rear ends of said levers being provided with handles 24. It will be noted that when the handle 24 of the levers are brought together the expanding ring will be contracted to permit the device to be inserted in a drill hole and that when said levers are released the ring or band 20 will expand and press the packing flange 15^b in contact with the wall of the drill hole.

In using my invention the drill hole is started with the large size bit and made deep enough to receive the tubular member or mouth piece of the device, and owing to the peculiar construction of the latter, it

will be seen that the necessity of an extra tool or bit to enlarge the drill hole is obviated. On referring to Fig. 1 it will be seen that the exhaust from the pneumatic drilling machine M passes through the bit 65 B, which is tubular and serves to drive the dust inwardly from the bottom of the drill hole and into the collecting casing or chamber as indicated by the arrows in said figure. The dust and chippings from the drill will 70 settle on the bottom of the casing, and the air will pass out of the same either through the porous material from which it is made or else through the screen or filter provided at its outlet portion. 75

Having thus described the invention, what is claimed is:

1. A dust arresting device of the class described, comprising a casing having diametrically adjustable necks, means to fit 80 and secure one of said necks on a drill, a diametrically adjustable tubular member in the other neck and for insertion in a drill hole, and diametrically adjustable means to clamp the last named neck on the said tubular member. 85

2. A dust arresting device of the class described, comprising a casing of flexible material having means to permit the discharge of air and prevent the discharge of dust 90 therefrom, the said casing being further provided with diametrically adjustable necks, one for engagement with a drill and having diametrically adjustable means to secure said neck on the drill, a tubular longitudinally adjustable member in the other neck, and for insertion in a drill hole, and diametrically adjustable means to clamp the last named neck on the said tubular member. 95

3. In a dust arresting device of the class 100 described, the combination of a dust and air receiving casing having a flexible diametrically adjustable neck, a diametrically adjustable tubular member in the said neck and provided near one end with stop devices 105 engaged by said neck, and diametrically adjustable clamping means on said neck coacting with said stop devices to secure said neck on said tubular member against longitudinal displacement and also serving to 110 clamp said neck on said tubular member irrespective of the diametrical adjustments of the latter.

In testimony whereof I hereunto affix my signature in the presence of two witnesses. 115

WILLIAM E. DWYER.
